CLAIM

The ornamental design for a decorative watch winder band, as shown and described.

DESCRIPTION

FIG. 1 is a perspective view of a watch winder including a decorative band in accordance with our new design, as seen from above;

FIG. 2 is a top plan view thereof;

FIG. 3 is a right side view;

FIG. 4 is a bottom plan view thereof;

FIG. 5 is a left side view thereof;

FIG. 6 is a front view thereof; and,

FIG. 7 is a rear view thereof.

In the drawings, the broken lines represent portions of the decorative watch winder band that form no part of the claimed design. The broken lines showing the watch winder represent environment of the claimed design and form no part thereof.
